UNITED STATES PATENT OFFICE

2,325,711

HYDRAULIC DOOR CHECK

David J. Seaman, Battle Creek, Mich.

Application August 2, 1940, Serial No. 349,408

6 Claims. (Cl. 16—54)

The present invention relates to hydraulic door checks and more particularly to a door check particularly adapted to be disposed within a door pivoted from the top and bottom thereof having about the axis of rotation a post of arcuate cross-section of the character disclosed in my Patent No. 2,184,259.

Door checks and closers of the character employing cams and springs in association with the movement of a hydraulic fluid have been used heretofore but have not been satisfactory for the reason that the servicing of them has been difficult and frequently required an adjustment, which adjustment required a skilled mechanic. According to the present invention, a hydraulic door check has been provided which is rugged and of few parts, thereby not being subject to frequent service requirements and a door check which may be adjusted readily by anyone as the conditions require. The desirability of having a hydraulic check readily adjustable will be understood when it is realized that hydraulic checks are generally employed in public buildings, such as stores, for instance, and it is desirable to have the tension of the checks set so that the door will properly close but will not require too much effort to move it open. However, when a door is set with such a minimum tension, the tension is not sufficient to prevent the door from being blown open by a strong wind in the street. Such an undesired opening, not only permits the blowing of dust and dirt into the building, but also makes the front portion of a store, for instance, most uncomfortable for sales persons. According to the present invention, the check may be readily adjusted in a few moments to increase the tension to take care of the added tension requirements due to the outside wind and when the wind has abated, the adjustment may be readily returned to its former state.

An object of the invention is to provide a hydraulic check for doors, the tension of which may be adjusted in a few moments by anyone.

Another object of the invention is to provide a hydraulic check housed in a unit which may be readily inserted in a door and removed therefrom for the purpose of servicing.

A further object of the invention is to provide a hydraulic check associated with the pivoting pin of the door, the pivoting pin being employed to support moving parts for sliding movement and to conduct through suitable ports therein hydraulic fluid from one chamber to another during opening and closing movement of the door.

A still further object of the invention is to provide a hydraulic check having two chambers, the effective volumetric capacity of which is changed during the opening and closing of the door requiring a flow of hydraulic fluid from one of the chambers to the other to control the speed of opening and closing, wherein one of the chambers comprises a reservoir for the hydraulic fluid.

These and other objects will be apparent from the following specification when taken with the accompanying drawing in which:

Fig. 1 is a vertical section of a portion of a door including the check according to the present invention.

Fig. 2 is a section on the line II—II of Fig. 1, and

Fig. 3 is a section on the line III—III of Fig. 1.

Referring particularly to the drawing, the reference character 1 indicates a door pivotally supported in a frame 2 by means of an upper pin 3 and a lower pin not shown. Concentric with the axis of the pin 3 is a post 4, tubular in form and disclosed more particularly in my aforesaid patent where a method of securing the door 1 and the post 4 together is also shown.

The pin 3 is supported from the frame 2 by means of a support 5 disclosed more particularly and claimed in my co-pending application, Serial No. 349,407, filed Aug. 2, 1940. The support 5 comprises a cylindrical member 6 having therein a squared opening 7 for receiving the squared upper end 8 of the pin 3. The cylindrical member 6 is telescopically movable in a cylindrical member 9. Downward movement of the member 6 is limited by a shoulder 10 thereon engaging with a shoulder 11 of the member 9. Rotary movement of the member 6 with respect to the member 9 is prevented by means of a set screw 12.

The check, according to the present invention, is housed in a cylinder 15, having end caps 16 and 17. The cylinder 15 with its caps is secured in some suitable manner in the post 4. The upper end of the pin 3 is supported in the cap 16 by a bearing 18 and the leakage of hydraulic fluid from within the check, past the pin 3, is prevented by an oil seal 19 of some suitable form.

The lower or inner end of the pin 3 is supported in a bore 20 in the cap 17. On the upper surface of the cap 17 is provided a cam 21 for acting against a follower 22 which consists of a piston 23 having depending ears 24 on which are mounted rollers 25. The cam 21 is cylindrical in form with diametrically opposed parts there-

of of the same relative height which simultaneously engage with the rollers 25 which are diametrically disposed on opposite sides of the axis of the pin 3 which is the axis of rotation of the door 1. Preferably the piston 23 is provided with rings 26 to prevent the escape of hydraulic fluid therepast.

The space between the piston 23 and the cap 17 comprises a chamber in which the cam 21 and the follower 22 are disposed. Above the piston 23 and between it and the cap 16 is another chamber in which is disposed about the pin 3 a helical spring 30, bearing at the lower end thereof against the piston 23 and at the upper end thereof against a thrust bearing 31 which is mounted on an abutment 32. The abutment in turn is threadably secured to the pin 3 and is provided with a plurality of circumferential openings 33. Opposite the openings 33 in the post 4 and the cylinder 15 is an opening 34 for permitting access to the openings 33 whereby a tool may be inserted in the openings 33 to rotate the abutment 32 to adjust the tension of the spring 30 on the piston 23.

The piston 23 is provided with an upwardly extending sleeve 35 disposed concentrically about the pin 3. The pin 3 is splined as at 36 to the sleeve 35 to permit longitudinal movement of the sleeve 35 and the piston 23 with respect to the pin 3 under the action of the cam 21 but to maintain the piston 23 and the follower 22 against rotative movement with respect to the pin 3.

The bore 29 is provided with an extension 37, extending downwardly to intersect a bore 39. The bore 38 communicates with a bore 39 communicating with the cam and follower chamber. For controlling the flow of hydraulic fluid between the bores 38 and 39, there is provided in the bore 39 a needle valve 40 under the control of a screw 41 to which external access may be had through an opening 42 in the post 4. An oil seal 43 is arranged about the screw 41 to prevent leakage of hydraulic fluid. By adjusting the screw 41 and thus the needle valve 40, the flow of hydraulic fluid passing through the bores 39, 38 and 37 during the closing of the door, and thus the speed of closing, may be controlled, although it will also be understood that the closing speed is also under the control of the spring 30, the tension of which may be adjusted by movement on the abutment 32.

Flow of the hydraulic fluid of the check during the opening movement of the door is through the bore 37, the bore 44 and the bore 39. The bore 44 is under the control of a ball check valve 45, urged against its seat 46 by a spring 47. Access to the ball check 45 and its associated parts for original installation and for servicing is through a bore 48, normally closed by a plug 49.

In operation, the check, according to the present invention, is first furnished with a hydraulic fluid which fills the cam and follower chamber completely and the spring chamber to a level such that the minimum volume of hydraulic fluid therein is greater than the maximum volume of the cam and follower chamber. Hydraulic fluid is furnished through an opening 50 normally closed by a plug 51. In order to permit the hydraulic fluid to flow downwardly into the cam and follower chamber and into the various fluid controlling bores, the screw 41 may be removed or partially removed. Assuming that the check has been properly filled with hydraulic fluid and the door is moved to an open position, during the opening movement the post 4 will rotate with

respect to the pin 3 and carry with it the cam 21 which will in turn act against the follower 22 to move the piston 23 upwardly. As the result, the volume of the cam and follower chamber is increased and hydraulic fluid flows from the spring chamber through ports 53 in the sleeve 35 to a supplementary annular chamber 54 around the pin 3. From the chamber 54 the fluid flows through a transverse bore 55 in the pin 3 to an axial bore 56 in the pin 3 which communicates with the bore 29 and the extension 37 of the bore 29. Some of the fluid will pass the needle valve 40 into the bore 39 but the greater portion of the fluid will flow from the bore 37 through the bore 44 to the bore 39, and from it to the cam and follower chamber, due to the fact that the ball check valve 45 will be moved from its seat 46.

As soon as the door starts to close the fluid will return from the cam and follower chamber to the spring chamber, but since the direction of the flow of the fluid will close the ball check valve 45, all of the fluid must flow past the needle valve 40. In practice the needle valve 40 will be adjusted to permit only a slow return of the door. The return movement of the door is accomplished by the force of the spring 30 bearing against the piston 23 and thus the follower 22 to drive the rollers 25 down the surfaces of the cam 21 to rotate the door in a closing direction.

It will be understood that with the door check of the character described, if the door opens to 90° position or more, the shape of the cam 21 will cause the door to continue in its opening direction. Accordingly, if this is undesirable, suitable stops should be provided to limit the opening to slightly less than the 90° point.

It will be understood that the ball check valve 45 and the port 44 may be dispensed with if it is not desired to have a quick opening movement.

In view of the fact that the volume of oil in the spring chamber is greater than the maximum volume of the cam and follower chamber, it will be apparent that when the door is opened to its widest position and the follower 22 is in its uppermost position, there will still be a reserve supply of hydraulic fluid remaining in the spring chamber. Accordingly, there may be a substantial loss of hydraulic fluid from the check with no ill effects on the operation so long as the minimum volume thereof in the spring chamber is equal to the maximum volumetric capacity of the cam and follower chamber.

When the check is to be drained of hydraulic fluid for the purposes of flushing and refilling, or for servicing, the screw 41, together with the needle valve 40 are removed and a rubber hose inserted in the opening. It will be observed that since the ports 53 communicating with the supplementary chamber 54 are at the lowermost portion of the spring chamber all of the hydraulic fluid in the spring chamber may be drained. It will be appreciated that for normal operations and for draining of hydraulic fluid of the check, the hydraulic fluid is replaced by air entering through the opening 34. Further, instead of providing the filling opening 50, if desired, the check may be filled through the opening 34 by screwing the abutment 32 upwardly until it clears the opening 34.

Another feature that may or may not be employed as is desired is the squared projection 60 at the bottom of the cap 10 which is shown fitted in a squared opening 61 in a member 62 permanently secured to the post 4. As will appear particularly from Fig. 1, instead of securing the

cylinder 15 in the post 4 by some other method, the projection 60 may be provided to fit in the squared opening 61. With this construction, the cylinder 15 together with its check enclosed is maintained in the post 4 by gravity and is maintained against rotation with respect to the post 4 by the square projection 60.

Having thus described my invention, what I desire to secure by Letters Patent and claim is:

1. A door check for controlling the movement of a door in a frame comprising a cylinder adapted to be supported by said door, a pivot pin for said door adapted to be fixed with respect to said frame and projecting into said cylinder, a cap for one end of said cylinder, said cap supporting said pin, a cam in said cylinder and supported by said cap, a follower in said cylinder, slideable on said pin and being splined thereto, a spring in said cylinder having one end supported with respect to said door, urging said follower into engagement with said cam, a piston comprising a portion of said follower dividing said cylinder into two chambers, one housing the spring and the other housing said cam and follower, said cam being active upon opening of the door to move said follower axially of said pin in said cylinder against the action of said spring, said spring upon removal of the opening force being active to force said follower against said cam to close the door, a hydraulic fluid in said chambers, and port means for controlling the flow of fluid between said chambers during opening and closing movement of said door to control the rate of opening and closing thereof.

2. A door check for controlling movement of a door in a frame, comprising a cylinder adapted to be supported by said door, a pivot pin for said door adapted to be fixed with respect to said frame and projecting into said cylinder, means supported with respect to said cylinder for supporting the inner end of said pin, a cam within said cylinder and supported with respect thereto, a helical spring in said cylinder substantially concentric with said pin, a follower in said cylinder between said spring and said cam, said spring urging said follower against said cam, and an abutment supported in said cylinder for receiving the thrust of said spring and for movement axially of said spring, said abutment being adjustable for adjusting the tension of the spring.

3. A door check for controlling movement of a door in a frame, comprising a cylinder adapted to be supported by said door, a pivot pin for said door adapted to be fixed with respect to said frame and projecting into said cylinder, means supported with respect to said cylinder for supporting the inner end of said pin, a cam within said cylinder substantially concentric with said pin, a follower in said cylinder between said spring and said cam, said spring urging said follower against said cam, an abutment threadably connected to said pin for opposing the thrust of said spring, and means to rotate said abutment

on said pin to provide movement axially of said pin to adjust the tension of said spring.

4. A door check for controlling the movement of a door in a frame comprising a cylinder adapted to be supported by said door, a pivot pin for said door adapted to be fixed with respect to said frame and projecting into said cylinder, a cap for one end of said cylinder, said cap supporting said pin, a cam in said cylinder and supported by said cap, a follower in said cylinder, slideable on said pin and being splined thereto, a spring in said cylinder having one end supported with respect to said door, urging said follower into engagement with said cam, a piston comprising a portion of said follower dividing said cylinder into two chambers, one housing the spring and the other housing said cam and follower, said cam being active upon opening of the door to move said follower axially of said pin in said cylinder against the action of said spring, said spring upon removal of the opening force being active to force said follower against said cam to close the door, a hydraulic fluid in said chambers, and port means for controlling the flow of fluid between said chambers during opening and closing movement of said door to control the rate of opening and closing thereof, said port means comprising a cavity in said cap beneath said pin, a port in said pin extending axially thereof providing a communication between said spring housing chamber and said cavity, a port between said cam and follower housing chamber and said cavity, means restricting said last named port, and a by-pass check valve providing communication between said last named port and said cavity for permitting the flow of hydraulic fluid therethrough from said cavity but not into said cavity.

5. The invention as defined in claim 3, wherein said cylinder is provided with an opening opposite said abutment for exposing said abutment to permit adjustment thereof from without said cylinder.

6. A door check for controlling movement of a door in a frame, comprising a cylinder adapted to be supported by said door, a pivot pin for said door adapted to be fixed with respect to said frame and projecting into said cylinder, means within said cylinder for supporting the inner end of said pin, a cam within said cylinder and supported with respect thereto, a helical spring in said cylinder, a follower in said cylinder operatively between said spring and said cam, said spring urging said follower against said cam, a driving connection between said follower and said pin for moving said door with respect to said pin, and an abutment supported in said cylinder for receiving the thrust of said spring and for movement axially of said spring, said abutment being adjustable for adjusting the tension of said spring.

DAVID J. SEAMAN.
